DESIGN FOR A CASE FOR PIANO OR THE LIKE

Alexander P. Brown, Beechhurst, N. Y.

Application February 26, 1946, Serial No. 126,938

Term of patent 14 years

(Cl. D56—9)

To all whom it may concern:

Be it known that I, Alexander P. Brown, a citizen of the United States of America, residing at 160—18 7th Ave., Beechhurst, in the county of Queens and State of New York, have invented a new, original, and ornamental Design for a Case for Piano or the like, of which the following is a specification, reference being had to the accompanying drawing, forming part thereof.

Fig. 1 is a front elevational view of a case for piano or the like showing my new design;

Fig. 2 is a side elevational view;

Fig. 3 is a top plan view;

Fig. 4 is a rear elevational view, and

Fig. 5 is a bottom plan view.

I claim:

The ornamental design for a case for piano or the like, substantially as shown.

ALEXANDER P. BROWN.
